US0D1088169S

(12) **United States Design Patent** (10) Patent No.: **US D1,088,169 S**
(45) Date of Patent: **** Aug. 12, 2025**

(54) **FIREARM FRAME**

(71) Applicant: **Palmetto State Armory, LLC**,
Columbia, SC (US)

(72) Inventors: **Zach Burris**, Summerville, SC (US);
Stephen Williams, Summerville, SC
(US)

(73) Assignee: **Palmetto State Armory, LLC**,
Columbia, SC (US)

(*) Notice: Patent file contains an affidavit/declaration
under 37 CFR 1.130(b).

(**) Term: **15 Years**

(21) Appl. No.: **29/827,940**

(22) Filed: **Feb. 23, 2022**

(51) LOC (15) Cl. **22-01**

(52) U.S. Cl.

USPC **D22/104**

(58) **Field of Classification Search**

USPC D14/418; D21/567, 572-574; D22/103,
D22/104, 108, 117, 199

CPC F41A 19/14; F41A 19/22; F41A 19/42;
F41A 19/45; F41A 19/38

See application file for complete search history.

(57) **CLAIM**

The ornamental design for a firearm frame as shown and
described.

DESCRIPTION

FIG. 1 is a top front perspective view of the firearm frame;
FIG. 2 is a top back perspective view of the firearm frame;
FIG. 3 is a front view of the firearm frame;
FIG. 4 is a back view of the firearm frame;
FIG. 5 is a left side view of the firearm frame;
FIG. 6 is a right side view of the firearm frame;
FIG. 7 is a top view of the firearm frame; and,
FIG. 8 is a bottom view of the firearm frame.

The broken lines depict portions of a firearm frame that form
no part of the claimed design. The name plates and magazine
well of a firearm frame shown in broken line that form no
part of the claimed design.

1 Claim, 6 Drawing Sheets
